[57] **CLAIM**

The ornamental design for a center loaded citizens band antenna, as shown.

DESCRIPTION

FIG. 1 is a front elevational view of a center loaded citizens band antenna showing our new design, the rear being a mirror image thereof;

FIG. 2 is an enlarged front elevational view thereof with portions broken away for convenience of illustration;

FIG. 3 is an enlarged top plan view thereof; and

FIG. 4 is an enlarged bottom plan view thereof.
